INVENTOR
JOHN E. ERICKSON
BY
Richard Cook
ATTORNEY

UNITED STATES PATENT OFFICE.

JOHN E. ERICKSON, OF SEATTLE, WASHINGTON.

DOORCHECK.

Application filed September 24, 1925. Serial No. 58,319.

This invention relates to improvements in door checks, and similar devices and has for its principal object to provide a mechanism adapted to be used with various types of hingedly mounted doors as a means of yieldably holding the door at different open positions to which it might be moved and which embodies a means that may be actuated to positively retain the door in closed position or at any open position.

More specifically stated, the invention resides in the provision of a door check embodying a series of rigid, pivotally joined bars, or links, adapted for pivotal connection with the door and also with a stationary part of the door frame, in such manner that there will be movement of the links relative to each other incidental to opening or closing movement of the door which will cause one of the links to move slidably within a fixed guide embodying a friction brake, or clamp, whereby a holding tension is placed on the link so as to prevent movement of the door except by the placing of sufficient pressure against it to overcome the holding pressure or tension of the brake.

Another object of the invention is to provide means for increasing or decreasing the tension provided in the brake so that more or less pressure will be required to close and open the door.

Other objects reside in the various details of construction of the various parts therefor and in their mode of operation.

In accomplishing these and other objects of the invention, I have provided the improved details of construction, the preferred forms of which are illustrated in the accompanying drawings, wherein—

Figure 1 is a perspective view of a truck door equipped with a check embodied by the present invention showing the door being held thereby in open position.

Figure 2 is a plan view of the device showing the relation of parts when the door is open.

Figure 3 is a plan view illustrating the relation of the various parts of the device when the door is closed.

Figure 4 is an enlarged section, taken on line 4—4 in Figure 2, showing the guide bracket and brake.

Figure 5 is a detail view of the holding mechanism.

Figure 6 is a view diagrammatically il-

lustrating a mechanism of an alternative type.

Referring more in detail to the drawings— 1 designates what may be a closed truck body of that type generally used for delivery wagons, having an opening 2 at the rear that is fitted with doors 3 mounted by hinges 4 so as to swing horizontally between closed and open positions. Fixed to the inner side of the rail 5 that forms the top of the door frame or casing is a bracket 6 having an inwardly directed, horizontal flange 7 to which one end of a bar 8 is pivotally fixed by a rivet, or the like, 9, so that it may swing horizontally into and from the door opening. 60 As is shown best in Figures 1 and 2 the bracket 6 is disposed adjacent that side of the opening at which the door is hinged and the bar 8, by a connection presently described, is caused to swing horizontally into and from 70 the opening in accordance with closing or opening movement of the door. In order that this movement may not be interrupted when the door is fully opened, the bar 9 is 75 curved laterally near its inner end, as at 10. 80

The outer end of the bar 9 is slidably contained within a sleeve 12 fitted thereto and which, at its outer end, is pivotally attached by means of a bolt 13 to a bracket 14 that is fixed to the door near or toward 85 its outer edge. The arrangement is such that as the door is moved between open and closed positions, the outer end of the bar is moved slidably within the sleeve. At its inner end the sleeve is provided with a longitudinally extended slot 15 with laterally directed spaced apart ears 16—16 at opposite sides of the slot through which a bolt 17 extends and which is provided with a wing nut 18 that may be tightened on the bolt to clamp the sleeve tightly against the bar to lock the door in open position.

Pivottally fastened by means of a rivet 20 to the bar 9 near its inner end, is a straight bar 21 which is slidably within a clamping bracket 22 that is fixed to the inner side of the top rail 5 of the door frame at some distance spaced from the bracket 6. The bracket 22 has an inwardly turned horizontal flange 22' across which the bar 21 slides beneath a plate 24 that is clamped across the top surface of the bar by means of two bolts 25—25 extended through the flange 22' and plate and on which spring washers 26 are held by nuts 27 to press the plate against 105 the bar 21. 110

the bar to yieldably resist sliding movement of the bar through the clamp. The desired tension may be obtained by loosening or tightening the nuts.

5 With the parts constructed and assembled as described, it is apparent that when the door is in open position, as shown in Figure 2, the bar 21, as connected with the bar 8, acts as a brace for holding the door in open 10 position. The tension of the brake may be sufficient that it will require considerable pressure on the door 3 to cause the bar to slide within the clamp and thus the door will not be swung to closed or open position 15 by wind or by an unlevel position of the door. If it is desired to positively hold the door to hold it at any adjusted open position, this may be done by tightening the nut 18 to clamp the sleeve 12 against the bar 8 20 so that it cannot slide therein.

When the door is closed the bar 21 still acts as a brace against bar 8 to hold the door closed for the reason that the curve formed at the inner end of bar 8 throws the 23 pivot point 20 inside of the line between the pivot point 9 and clamp through which bar 21 slides. The movement of the door to open position is limited by means of a pin 28 through the end of bar 21, which acts 28 as a stop when brought in contact with bracket 22.

In order to provide means for positively holding the doors through the mechanism above described, I have provided a bracket 35 30 on the under side of the sleeve 12 on which a cam 32 is pivotally mounted and which by rotation may be tightened against the bar 8 through a slot 33 cut in the under side of the sleeve.

40 The cam may be rotated through mechanism comprising a link 34 that is pivotally fixed at its inner end to the cam and at its outer end to one arm of a bell crank 35 mounted on the door. The other arm of the bell crank has a link 36 attached thereto which extends downwardly and is pivotally connected with an arm or lever 37 that extends laterally from a shaft 38 that is rotatable in the door. At its outer end the shaft 45 has a lever 39 whereby it may be rotated to effect movement of the cam between holding and releasing positions. The lever arm 39 is provided with a slot 40 for receiving a fixed post 41 on the door and the lever may be fixed against movement by suitable means such as a padlock 42 to prevent release of the cam.

While I have described the door check and lock as used on a truck door it is readily apparent, and it is intended, that such devices be used for all types of doors such as those in residences, offices, passenger cars, garages, delivery wagons, etc., as well as for hinged windows, transoms and box covers.

45 In figure 6 I have illustrated diagram-

matically an alternative mechanism designed for control from the driver's seat of an automobile or other vehicle employing an internal combustion engine as its motive means. The manipulation of the device from holding to released position also closes or opens the circuit to the motor so that the motor cannot operate while the vehicle doors are open or released.

The construction may be of various types 75 but one which is easily operable and which is here shown consists of a shaft 50 that is adapted to be rotatably supported in brackets 51 so as to extend within the top of the vehicle from front to back. At its rear end the shaft has a lever arm 52 fixed thereto for actuating a locking pin 53 carried by a bracket 54 into and from an aperture 55 in the bar 21 to retain the door closed. The shaft 50, at its forward end, has an arm 56 attached to which a spring 57 is fixed to rotate the shaft to release the lock, and a cable 58 is attached thereto and extended over suitable guide rollers 59 to a control lever 60 which is located in a position easily accessible to the driver of the vehicle and which, when pushed downwardly causes, through the connection shown, the shaft 50 to be rotated to release the lock pin 53 from the bar 21.

When the lever 60 is down, it engages with two contacts 61 and 62 in the ignition circuit so as to close the circuit to the motor and when in raised position, it disengages the contacts to open the circuit. This insures that the vehicle cannot be in motion when the doors are unfastened. Loss of material and damage to doors is thus avoided.

It is further apparent that various changes 10 in the details of construction could be made without departing from the spirit of the invention and for this reason I do not wish to be confined only to the details herein illustrated.

Having thus described my invention, what I claim as new therein and desire to secure by Letters Patent, is:

1. A door check comprising telescopically rigid members having ends pivotally attached, respectively, to the door and its frame, a yieldable clamping brake fixed to the door frame and a brace bar pivotally fixed at one end to one of the telescopically joined members and slidably at its other end 11 within said clamping brake.

2. A door check comprising a sleeve, a bar 12 slidable at one end in the sleeve, means for pivotally attaching the sleeve to a door, means for pivotally mounting the outer end of the bar from the door frame, a brace bar pivotally attached at one end to the first named bar and a guide fixed to the door frame to slidably contain the brace bar and embodying means for yieldably resisting 13

slidable movement of the bar therein and means for clamping the sleeve against the bar to lock the door against movement.

3. A door check comprising a bar, a sleeve 10
slidable on one end of the bar, a bracket fixed to the inner side of the door frame, a bracket fixed to the door and means attaching the end of the bar and sleeve, respectively, to the brackets, a clamping brake fixed to the inner side of the door frame at a distance spaced from the first named bracket, a brace bar pivotally fixed to the first named bar and slidable within the clamping brake and a pin through the outer end of the brace 15
bar engageable with the clamping brake to limit outward movement of the door.

4. A door check comprising telescopically 20
rigid members having ends pivotally attached, respectively, to the door and its frame, a yieldable clamping brake fixed to the door frame and a brace bar pivotally fixed at one end to one of the telescopically joined members and slidable at its other end within said clamping brake, and means for 25
adjusting the tension of the clamping brake against the brace bar, locking means embodying a cam mounted on the sleeve to engage with the bar therein and mechanism operable for adjusting the cam between locking and released positions.

5. A door check comprising telescopically

rigid members having ends pivotally attached, respectively, to the door and its frame, a yieldable clamping brake fixed to the door frame and a brace bar pivotally fixed at one end to one of the telescopically joined members and slidable at its other end within said clamping brake, and means for 35
adjusting the tension of the clamping brake against the brace bar, holding means embodying a cam mounted on the sleeve to engage with the bar therein and mechanism operable from the outside of the door for 40
adjusting the cam between holding and released positions.

6. In a vehicle of the character described, a door check comprising telescopically rigid members having ends pivotally attached, respectively, to the door and its frame, a yieldable clamping brake fixed to the door frame 50
and a brace bar pivotally fixed at one end to one of the telescopically joined members and slidable at its other end within said clamping brake, a locking pin movable into and from holding engagement with the brace 55
bar, and mechanism operable from the driver's seat of the vehicle for moving said pin between holding and releasing positions.

Signed at Seattle, King County, Washington, this 28th day of August, 1925. 60

JOHN E. ERICKSON.
